[57] CLAIM

The ornamental design for a novelty sculpture, as
shown and described.

DESCRIPTION

FIG. 1 is a top plan view of a novelty sculpture showing
my new design;

FIG. 2 is a side elevational view thereof;

FIG. 3 is a left end elevational view thereof; and

FIG. 4 is a right end elevational view thereof.

The bottom surface is planar and unornamented.

FIG. 1

FIG. 2

FIG. 3

FIG. 4
